UNITED STATES PATENT OFFICE.

HARRY ISRAEL HUMPHREY, OF BIRMINGHAM, ENGLAND.

CHILD'S CARRIAGE.

SPECIFICATION forming part of Letters Patent No. 522,117, dated June 26, 1894.

Application filed February 6, 1894. Serial No. 499,237. (No model.) Patented in England November 8, 1892, No. 20,110.

To all whom it may concern:

Be it known that I, HARRY ISRAEL HUMPHREY, a subject of the Queen of Great Britain, and a resident of Birmingham, in the county of Warwick, England, have invented 5 certain new and useful Improvements in Children's Mail-Carts or Bassinets, (for which I have obtained a patent in Great Britain, No. 20,110, dated November 8, 1892,) of which the following is a full, clear, and exact specification.

This invention relates to mail carts or children's carriages and aims to provide a mail cart which can be readily converted into a 15 single or double mail-cart or carriage or as a bed or bassinet.

The improvement consists in the novel features to be more fully described and claimed hereinafter, reference being made to the annexed drawings, in which—

Figure 1. is a sectional side elevation of my invention. Fig. 2. is a sectional side elevation of same when in position for use as a double bassinet or mail cart; Fig. 3. a plan view of 25 swiveling seat; Fig. 4 a sectional elevation of catch piece *h*; Fig. 5. a sectional side elevation of a modified arrangement of my invention.

Referring to Figs. 1, 2, and 3, *a* is the seat 30 which is attached to the body of the frame of the cart through the medium of the hinged flap or piece *b*. In Fig. 1 the seat *a* is shown in its folded or collapsed position. The prongs or catch pieces *c* attached to the seat enter 35 the sockets *c'* attached to the shafts or handles *d* when the seat *a* is in its extended position. The seat *e* has a false or hinged bottom *f* which folds over in the direction of the arrow 1 and forms a bed if desired. The seat 40 *a* is pivoted at *g* and is secured in either position by a spring catch or other suitable device such as that shown at *h*, Fig. 4 so as to

lock the seat *a* in either position. When the seat *a* is in its extended position and the hinged bottom *f* is folded over in the direction of the arrow 1, the same forms a bassinet. If now the seat *a* be turned upon its pivot *g* and the hinged bottom *f* retained in the same position a child may be in the one space and another sit in the seat *a* and if the hinged bottom *f*, be folded over onto the seat *e* and the seat *a* be turned upon its pivot *g* two children may sit facing each other with their feet in the well or space formed by the hinged flap *b* and the body of the cart.

Referring to Fig. 5 in this modification the seat instead of folding down by being attached to a hinged flap slides in grooves *i* in the body and shafts *d* of the cart being constructed so as to turn on a pivot as previously described; 60 if desired, the hinged bottom *f* folding over as before when the seat *a* is in its extended position and forming a bassinet or bed. The flap *f*, is hinged at *j*, so as to take the position shown in Fig. 1 when the seat *a*, is collapsed or not extended for use.

With this description of my invention, what I claim, and desire to secure by Letters Patent, is—

In mail carts or bassinets in combination 70 therewith, a piece formed in two or more parts and forming one side of the well to one end of which is hinged a seat the other end being hinged to the bottom of the cart so that when in its collapsed or folded position said seat 75 forms a foot rest and when extended a seat, substantially as described.

In testimony that I claim the foregoing I have hereunto set my hand this 20th day of December, 1893.

HARRY ISRAEL HUMPHREY.

Witnesses:

BENJAMIN CLARK,
W. I. WEEKS.
